E. F. CLARK

TUBE FRAME

Filed May 24, 1924

Inventor:
Eugene F. Clark
by
Geo. N. Goddard, atty.

UNITED STATES PATENT OFFICE.

EUGENE F. CLARK, OF LEAKSVILLE, NORTH CAROLINA.

TUBE FRAME.

Application filed May 24, 1924. Serial No. 715,536.

This invention relates to tube frames for tuft weaving of the general type shown and described in Letters Patent of the United States No. 1,487,442, granted to me March 5 18, 1924, and is intended to improve that type of tube frame by providing a strong and durable construction that will make separable suspension means and spool-bearing brackets applicable to tube frames in 10 which is employed a wooden carrier-bar instead of a tubular carrier-bar.

With these and other objects in view, the invention comprises, generally speaking, a carrier bar, preferably of wood, provided at 15 its end with a protective and connecting ferrule overlapping the end portion of the carrier-bar for a substantial distance to afford a strong and rigid construction, while still making it possible to carry the row of tuft 20 tubes out nearly to the ends of the bar.

This and other features of the invention will be described in the following specification and will be defined in the claims here- 25 to annexed.

In the accompanying drawings I have illustrated a preferred construction and arrangement embodying the principles of the present improvement in which:

Figure 1 is a rear elevation of an end portion of the carrier-bar and its suspension means and spool-bearing bracket.

Figure 2 is an end elevation of the opposite end of the bar.

Figure 3 is a front perspective of the end 35 portion of the carrier-bar with the spool-bearing bracket and the suspension hanger separated therefrom to show details of the parts.

Figure 4 is a vertical cross section showing the relation of the carrier-bar to the surrounding ferrule and the attaching wings by which the spool-bracket and the suspen- 40 sion hanger, respectively, are held in place.

The spool-bearing bracket in its general 45 arrangement and construction is similar to that shown in my former patent and so likewise is the suspension hanger.

In this case the carrier bar 1, is presum- 50 ably made of wood with its top and bottom faces rabbetted or cut away as shown at 1^b, 1^c, for the reception of the angular attach- 55 ing feet of the spool-bearing bracket and of the suspension hanger, respectively. At the

extreme end the front and rear faces of the wooden carrier-bar are cut away for a 55 shorter distance to form a short tenon 1^d, to make room for the interposed side wings or attaching members of the spool bearing-bracket and of the hanger, respectively.

A strong metal ferrule 2, receives the cut 60 away end portion of the bar which it overlaps for a substantial distance to give the requisite area of support and the reinforcement for the bar. In order to make provision for carrying the row of tuft tubes 65 that are usually soldered or otherwise secured to a longitudinal attaching strip, close to the end of the carrier-bar structure, the front wall 2^a of the hollow ferrule extends inward only a short distance, leaving the remainder 70 of the front open to the inner end of the ferrule. This allows the tuft-tube carrying strip to be secured to the wooden bar a substantial distance beyond the inside end of the ferrule, thereby utilizing practically the entire 75 length of the bar for the tuft tubes.

The spool-bearing bracket 3, has at its upper end an open bearing 3^a, to form a support for the spool journal. This upright portion is inwardly offset, and across the 80 offset portion is secured a spring metal keeper 4, riveted or otherwise secured at 4^a against the inside face of the spool bracket, thence extending upward over the outside 85 face of the spool bracket, its middle portion being cut away to permit its application to the bearing bracket in the manner shown in Figure 1. At the left of the upper portion of the bearing recess 3^a, the spring keeper 4 is formed with an angular inset struck-up tongue 4^b which normally overhangs the 90 yarn-spool journal but can be pressed outwardly to allow the journal to be lifted out of the open bearing.

The attaching means for securing the 95 spool-bearing bracket in position on the carrier-bar comprises parallel side wings 3^b, and a horizontal top wing 3^d which, after the ferrule is placed on the end of the carrier-bar, can be inserted between the sides 100 and top of the carrier-bar and the corresponding walls of the ferrule. The top attaching wing 3^d is provided with a longitudinal slot or notch 3^e to permit an attaching screw 30 to be passed through the top 105 wall of the ferrule and into the solid end

portion of the wooden bar without interfering with the removal of the spool-bearing bracket when desired. The top wall of the ferrule is also provided near its end with another hole 20 for allowing a short machine screw to be inserted in threaded engagement with the top wing 3^a.

The suspension means, in this case, comprises the upright hanger 5 whose lower portion is inwardly turned to form a bottom attaching wing or foot member 5^c, and in the angle between the upright portion 5 and the foot member 5^c are secured parallel attaching wings 5^b, provided with threaded holes 5^d for the reception of fastening screws which are passed through aligned holes in the front and rear walls of the ferrule and which pass through open notches or slots 3^e formed in the attaching wings 3^b of the spool-bearing bracket. An attaching screw 40 is inserted through the middle part of the bottom part of the ferrule through the slot 5^d of the suspension hanger, and into the solid end portion of the wooden carrier-bar. By this construction it will be seen that the hanger may be removed bodily by removing the attaching screw 40 and the shorter machine screws which are tapped into the holes 5^e, without disturbing the relation of either the ferrule or the spool-bearing bracket to the carrier-bar, thus leaving the spool in normal position. Furthermore, by removing the screws passing through the attaching wings of the spool-bearing bracket, the latter may be removed without disturbing the position of the ferrule which is still held in place by the attaching screws 30 and 40, and any additional screws that it may be desired to use. The above described construction and arrangement of parts it will be seen affords a very rigid and permanent connection to the spool-bearing bracket, the suspension means and the wooden carrier-bar, and yet permits the removal and replacement of the suspension hangers without causing the spool to drop out of place. Furthermore, both the suspension hanger and the spool-bearing bracket may be removed without disturbing the ferrule or without removing the wood screws 30, and 40 which secure the ferrule in place and whose repeated removal and insertion would soon cause an objectionable looseness of the fastening means. The spring-chain latch 6, is secured against the lower boss of the outer face of the suspension hanger by the machine screw 6^a, and consequently is removed bodily with the suspension hanger itself. The front face of the wooden bar 1, is cut away, as shown at 1^a, as shown in Fig. 4, to form a receiving face to which the tuft tube carrying strip is secured so as to leave a slight overhanging ledge to protect the yarn from the sharp upper ends of the tuft tubes. It

will also be noted that both the suspension hanger and spool-bearing bracket are made of rigid or stiff material sufficient to resist the strain of usage and avoid displacement or deterioration when subjected to pressure. 70

What I claim is:

1. In a tube frame for tuft weaving, the combination of a carrier-bar, of a hollow end extension surrounding the end portion of the carrier bar and forming a protective 75 ferrule therefor, the front wall of said ferrule being open to the inner end of the ferrule to receive a tuft-tube carrying strip, a spool bearing bracket detachably secured to the ferrule, and suspension means separately and detachably secured to the ferrule, substantially as described.

2. In a tube frame for tuft weaving, the combination with a wooden carrier-bar, a hollow end extension secured to the end portion of the bar to form a protective connecting ferrule, a spool-bearing bracket of rigid material provided with inwardly projecting attaching members insertable between the top and side faces of the carrier-bar and the corresponding walls of the ferrule, a suspension hanger provided with inwardly projecting attaching members insertable between the side and bottom faces of the carrier-bar and the corresponding walls of the ferrule, and fastening means for securing the carrier bar, the ferrule, the spool-bracket and the hanger in assembled relation while allowing their separate removal, substantially as described. 95

3. In a tube frame for tuft weaving, the combination with a wooden carrier-bar, of a hollow ferrule surrounding the end portions of the bar, a rigid spool-bracket having inwardly projecting attaching means insertable between the ferrule and the end portion of the bar; a hanger having inwardly projecting attaching means insertable between the ferrule and the end portion of the bar, the front wall of the ferrule being open from 100 its inner end to expose the front face of the bar for application of a tube-carrying strip thereto, and means for detachably securing the respective parts into assembled relation, substantially as described. 110

4. In a tube frame for tuft weaving, the combination with a wooden carrier-bar, of a ferrule secured around the end portion of the bar, a rigid spool-bracket provided with an inward attaching member insertable between the ferrule and the bar, a suspension hanger provided with an inward attaching member insertable between the bar and the ferrule, separate means for detachably securing the hanger and the spool bracket to the ferrule, whereby they may be separately removed without disturbing the attachment of the ferrule to the carrier-bar, substantially as described. 120

5. In a tube frame for tuft weaving, the 125

combination with a carrier-bar a protective ferrule secured around the end portion of the bar, a spool-bearing bracket of rigid material comprising an upright bearing arm, and an inward attaching member insertable between the bar and the ferrule and means for detachably securing the inward attaching member to the ferrule, thereby indirectly securing it to the bar, substantially as described.

6. In a tube frame for tuft weaving, the combination with a carrier bar, a ferrule surrounding the end portion of the bar and secured thereto, a suspension hanger provided with an angularly disposed attaching member insertable between the ferrule and the bar, means for detachably securing the hanger directly to the ferrule and thereby indirectly to the carrier bar whereby the suspension hanger may be removed without disturbing the means securing the ferrule to the bar, substantially as described.

7. In a tube frame for tuft weaving, the combination with a wooden carrier-bar, a surrounding ferrule detachably secured to the end portion of the bar, a spool-bearing bracket having an attaching member insertable between the bar and the ferrule, separate fastening means for detachably securing the hanger and the bracket to the ferrule, thereby permitting the separate removal of the hanger and the bracket with-

out disturbing the means for securing the ferrule to the bar, substantially as described.

8. In a tube frame for tuft weaving, the combination with a carrier-bar, of a ferrule surrounding the end portion of the bar and secured thereto, a spool-bracket having an angularly disposed lower end insertable between the bar and the ferrule and secured to the ferrule by attaching screws, the upright bearing portion of said bracket being formed with an open bearing recess, and a spring catch secured to the bracket to overhang the open bearing recess to retain the spool journal in the bearing, substantially as described.

9. A spool-bearing bracket for supporting the yarn-spool of a tube frame embracing a rigid angle piece comprising an upright bearing member provided with an open bearing recess, and a lateral foot member for attaching it to the tube frame, a spring arm secured against the inside face of the upright member and having its upper end portion located outside said upright with a journal-engaging tongue arranged to overhang a spool journal mounted in said recess, to normally retain the journal in place while yielding to permit its removal, substantially as described.

In witness whereof, I have subscribed the above specification.

EUGENE F. CLARK.
